FALSE EYELASH CONTAINER AND CURLER
Barbara J. McGivern, 18 Tresillian Road,
Downsview, Ontario, Canada
Filed Oct. 3, 1966, Ser. No. 583,820
8 Claims. (Cl. 132—31)

This invention relates to a container for storing false eyelashes of the type often worn by women.

One of the problems encountered by users of false eyelashes is the difficulty of maintaining the individual hairs of the eyelash in a curled or curved state such that the eyelash, when worn, will have a more or less natural appearance. Manufacturers of false eyelashes often recommend that users of their product employ a pencil or other small-diameter tubular instrument as a kind of mandrel upon which to wrap or wind the false eyelashes when they are not being worn. A strip of paper is commonly employed to cover the eyelash when it is wound upon the pencil, and a rubber band or the like is applied thereover to hold both in position.

The above procedure is troublesome and time-consuming, and in particular results in a false eyelash with a straight backing strip, rather than one conforming to the natural curve of the eyelid.

It is therefore an object of this invention to provide a simple open-shut container for false eyelashes which is adapted both to store and to curl them, without requiring a troublesome winding procedure.

It is an object of a preferred form of this invention to provide a container for false eyelashes which is adapted not only to store and curl the false eyelashes, but to display them advantageously as well.

It is a further object of a preferred form of this invention to provide a container for false eyelashes which is adapted to store the false eyelash in such a way that the backing strip of the eyelash retains the natural curve of the eyelid.

Accordingly, this invention provides a container for storing a false eyelash and for maintaining the hairs of the false eyelash in a desired profile, said container comprising: a bottom having a groove adapted to receive said false eyelash, the groove having a profile substantially matching the profile to be imparted to the hairs of said eyelash, and a top having a transparent protuberance shaped to fit complementally within said groove when the container is closed, such that a false eyelash within said groove can be simultaneously stored, curled, and viewed when the container is closed.

Two embodiments of this invention are shown in the accompanying drawings, in which like numerals refer to like parts throughout the several views, and in which:

FIGURE 1 is a partly broken-away perspective view of a false eyelash container;

FIGURE 2 is a sectional view taken along the line A—A of FIGURE 1, showing a first embodiment of this invention;

FIGURE 3 is a sectional view similar to that of FIGURE 2, showing a second embodiment of this invention; and

FIGURE 4 is a sectional view similar to FIGURES 2 and 3, showing a various of the first embodiment of this invention.

Hereinafter, the terms "eyelash" and "false eyelash" will be used to denote the whole of the item which is adhered to an eyelid: that is, the sticky or adherent backing strip in combination with a plurality of individual hairs which are secured thereto at intervals and extend therefrom all in the same direction. The individual hairs of each eyelash will be referred to as such.

2

Turning now to FIGURE 1, a false eyelash container shown generally at 10 is seen to consist of a bottom 11 and a top 12. Preferably, the top 12 is hingedly or otherwise connected to the bottom 11, although it is not necessary for the two parts to be connected at all. For convenience, a pin-type hinge 13 is shown in FIGURES 2 and 3 for the purpose of hingedly securing the top 12 to the bottom 11.

10 The bottom 11 has two grooves 14, each adapted to receive one false eyelash. As can be seen in FIGURES 2 and 3, each groove has a rounded profile. The curvature and length of the profile are chosen such as substantially to match the curl desired to be imparted to the hairs of a false eyelash.

15 In FIGURE 1, two false eyelashes 15 are shown received within the groove 14, and each eyelash 15 consists of an adhesive backing strip 16 and a plurality of individual hairs 17. In FIGURES 2 to 4 it can be seen that, with the backing strip 16 adhered near or at one of the 20 extremities of the profile of the groove 14, the individual hairs 17, when shaped to follow said profile, do not project beyond the opposite extremity thereof.

25 The bottom 11 shown in the figures consists of an outer portion 20 and an insert 21 provided with the grooves 14, and receivable within the outer portion 20. The top 12 has a lip 22 adapted to lodge within a cut-away portion 23 along the edge of the bottom 11, and to be secured thereto by any of several conventional means (not shown).

30 The outline of the grooves 14, i.e., the general shape of the grooves when viewed from above looking down into the groove, is curved to conform approximately to the natural curve of the eyelid. It is to be understood, however, that it is not essential to curve the groove outline in this way. The false eyelashes 15 could be made to fit inside a rectangular groove, or a groove curved somewhat differently to that shown in FIGURE 1. Nonetheless, it is desirable to store the false eyelashes in such a way that the backing strip 16 retains the natural eyelid curve, and therefore it is preferred that the outline of the grooves 14 be as shown. Furthermore, for display purposes it is of advantage to show the false eyelashes in the configuration which they are to be worn.

45 The top has two protuberances 24 which are shaped to fit complementally within the grooves 14 when the container is closed. With the false eyelashes 15 in position as shown in FIGURE 1, closure of the container 10 will cause the protuberances 24 to seat snugly within the 50 grooves 14, thereby holding the false eyelashes 15 in a curled and curved configuration.

55 The above description relates to the ability of the container 10 both to store and to curl false eyelashes, and these features constitute the present invention in its broad aspect. An additional inventive feature has particular relation to the protuberances 24, and this aspect will now be described.

60 The additional feature involves the use of the container 10 for display purposes, as well as for storing and curling false eyelashes. By using a transparent material such as a clear acrylic plastic for the top 12 (including the protuberances 24), it is possible to view the false eyelashes 15 in a closed container 10 by looking downwardly through the protuberances. Naturally, a view of the false 65 eyelashes 15 requires transparency only in the protuberances, and it is not necessary that the entire top 12 be so.

FIGURES 2, 3 and 4 show a number of alternative cross-sections for the protuberance 24. In FIGURE 2, the upper surface 26 of the protuberance 24 is planar and it will be appreciated that the resulting lenticular profile of the protuberance 24 will cause the latter to act in some degree as a lens, magnifying the false eyelashes 15 be-

neath. Naturally, a lenticular cross-section does not require that the upper surface 26 be planar. It is merely necessary that the upper surface 26 be spaced further from the rounded lower surface of the protuberance mid-way of the cross-section than it is at the extremities of the cross-section. FIGURE 4 shows two other configurations 26a and 26b for the upper surface of the protuberance 24, both of which result in a lenticular cross-section for the latter.

Alternatively, a lenticular cross-section can be dispensed with, and instead, the cross-section shown in FIGURE 3 can be employed. In FIGURE 3, the upper surface 27 of the protuberance 24 follows the curve of the rounded lower surface of the protuberance 24, and remains the same distance therefrom throughout the whole of the cross-section. Little distortion of the eyelash would be likely to occur with the cross-section shown in FIGURE 3.

It will be appreciated that, whereas the above description relates to a container 10 having two grooves 14, the essence of the invention is encompassed in a single groove 14 and its complementary protuberance 24. Two grooves 14 have been shown and described because it is common to sell false eyelashes in pairs.

The rounded surface of the grooves 14, and the complementary lower surface of the protuberances 24, have been shown with an approximately circular curvature. This has been done here for the sake of convenience only, and is not to be construed as a limiting feature. The only characteristic necessary for the groove 14 is that its profile, and more particularly the profile of the lower surface of the protuberance 24, be a close approximation to the curl it is desired to impart to the false eyelashes. Since a smooth curve is generally desirable for the curl in the hairs of a false eyelash, it follows that the profile of the groove 14 and of the protuberance 24 should be a smooth curve.

While preferred embodiments of this invention have been disclosed herein, those skilled in the art will appreciate that changes and modifications may be made therein without departing from the spirit and scope of this invention as defined in the appended claims.

What I claim as my invention is:

1. A container for storing a false eyelash and for maintaining the hairs of the false eyelash in a desired profile, said container comprising:

a bottom having a groove adapted to receive said false eyelash, the groove having a profile substantially matching the profile to be imparted to the hairs of said eyelash,

and a top having a transparent protuberance shaped to fit complementally within said groove when the container is closed, such that a false eyelash within said groove can be simultaneously stored, curled and viewed when the container is closed.

- 5 2. A container as claimed in claim 1, in which the protuberance is lenticular in cross-section, having a curvilinear lower surface and an upper surface which is spaced further from said lower surface mid-way of the cross-section than it is at the extremities of the cross-section, such that a false eyelash within the groove viewed from above the closed container appears magnified in size.
- 10 3. A container as claimed in claim 2, in which the upper surface of the protuberance is planar.
- 15 4. A container as claimed in claim 1, in which the upper surface of the protuberance is substantially equidistant from the lower surface thereof at all points.
5. A container as claimed in claim 1, in which the container is adapted to store and curl a pair of false eyelashes, the bottom having an additional groove for the other false eyelash, the two grooves being substantially identical, the top having an additional protuberance shaped to fit complementally within said additional groove when the container is closed.
- 20 6. A container as claimed in claim 1, in which the outline of the groove is curved to conform approximately to the natural curve of the eyelid.
7. A container as claimed in claim 6, in which the protuberance is lenticular in profile having a curvilinear lower surface and a planar upper surface.
- 30 8. A container as claimed in claim 6, in which the upper surface of the protuberance is substantially equidistant from the lower surface thereof at all points.
